CLAIM

The ornamental design for the toy castle convertible into a table and chair set, as shown and described.

DESCRIPTION

FIG. 1 is a front perspective view of a toy castle convertible into a table and chair set of this invention;

FIG. 2 is a front view of the toy castle configuration of this invention;

FIG. 3 is a right-side view of the toy castle of this invention;

FIG. 4 is a rear view of the toy castle of this invention;

FIG. 5 is a left-side view of the toy castle of this invention;

FIG. 6 is a top plan view of the toy castle of this invention;

FIG. 7 is a bottom plan view of the toy castle of this invention;

FIG. 8 is a perspective view of the toy castle when converted into a table and chair set of this invention;

FIG. 9 is a top plan view of the table and chair set of this invention;

FIG. 10 is a bottom plan view of the table and chair set of this invention; and,

FIG. 11 is a front view of the table and chair set, a left-side and right-side view being a mirror image thereto with exception to the broken line disclosure.

The broken lines are for illustrative purposes only and form no part of the claimed design.
